UNITED STATES PATENT OFFICE.

MORRIS U. BERNHEIM, OF CINCINNATI, OHIO, ASSIGNOR TO THE ALVEY-FERGUSON COMPANY, OF OAKLEY, CINCINNATI, OHIO, A CORPORATION OF OHIO.

CONVEYING SYSTEM.

1,278,426.

Specification of Letters Patent. Patented Sept. 10, 1918.

Application filed September 14, 1909, Serial No. 517,626. Renewed March 17, 1917. Serial No. 155,616.

To all whom it may concern:

Be it known that I, MORRIS U. BERNHEIM, a citizen of the United States, residing at Cincinnati, in the county of Hamilton and 5 State of Ohio, have invented certain new and useful Improvement in Conveying Systems, of which the following is a specification:

This invention relates to elevators and 10 more particularly to an elevator adapted to be used in conjunction with and as an element of a conveying system.

The purpose of the present invention is to 15 provide an improved elevator of this nature constructed to coöperate with endless traveling aprons arranged end to end in such manner that said aprons and the elevator provide means which will safely and rapidly transfer filled bags or other packages along 20 a level of readily variable length and in readily variable directions and from said level to a different one, and which is adapted to transfer such packages from wagons or cars and pile the same in any part of the 25 room of a warehouse or other place of storage or from such storage places to wagons or cars or from one part of a room to another part of the same room or from one room to another room on a different level. 30 While it is intended to claim herein the elevator, I will describe in detail the construction and operation of the system as a whole because the marked advantages of the elevator forming the subject matter of this application can best be appreciated by a thorough 35 understanding of the conditions under which it is used as well as the manner of using the same. The system of which this elevator forms a part is characterized by the 40 facts:

First: that it comprises a series of readily separable and unitable movable sections, each having a frame, an endless traveling apron, a shaft which extends lengthwise of 45 the frame, driving connections between the shaft and the apron adapted to impart positive movement to the latter in the direction of the length of the shaft, and universal connections between the confronting ends of 50 the several sections, whereby one of said shafts will be driven by another and each will impart the described traveling movement to the apron of its section, regardless

of the angle at which said shaft and apron of one section occupies with reference to the 55 similar parts of the next section;

Second: that it comprises an elevator which is readily removable from place to place, has an endless traveling apron which moves in planes whereby it is adapted safely 60 and without jar to the packages or its mechanism to receive packages from or deliver the same to the foregoing sections, and has a discharging slide, the delivering end of 65 which is adjustable laterally as well as vertically for delivering bags from the elevator to a predetermined place within the range of its adjustments, to a storage pile being built up by the system.

The parts are also characterized by features entering into the details thereof, whereby important advantages in respect of strength, effective utilization of power, portability, and ease of disconnections of sections and their assemblage into a system of 75 the required length, extending in required directions to and from any required place, are secured, all as will hereinafter fully appear.

The several objects of the invention are 80 well accomplished by the construction illustrated in the accompanying drawings serving to exemplify the invention. In the drawings

Figure 1 is a perspective view of one of 85 the conveyer-sections and a part of the contiguous one, arranged to convey the bags along a level and in a straight line.

Fig. 2 is a similar view of the inclined elevator or lowerer showing in dotted lines a 90 horizontal section at the base thereof.

Fig. 3 is a detail perspective view of a 95 slide leading from the delivering end of the elevator or lowerer.

Fig. 4 is a rear end view of said slide and 100 the portion of the elevator or lowerer to which it is secured.

Fig. 5 is a detail view, partly in section and partly in elevation of the pivotal support of the elevator or lowerer.

Fig. 6 is a side elevation of the lower 105 end of the elevator or lowerer.

Fig. 7 is a cross section thereon on the line 7—7 of Fig. 6.

Fig. 8 is similarly a cross section, but 110 taken on the line 8—8 of Fig. 6.

Fig. 9 is a cross section through one of the conveyer-sections taken on a line such as 9—9 of Fig. 1.

Fig. 10 is a top plan view of the motor and gearing of the apron-conveyer.

The same characters of reference designate the same parts in the several views.

A complete system made in accordance with the present invention is composed of 10 any desired number of portable apron-conveyer sections A, A' and an elevator or lower B also of the apron type.

The section A comprises a portable frame of suitable length and of a construction, 15 hereinafter set forth, whereby it is strong and light and furnishes guidance for an endless traveling apron of suitable character, here shown as composed of a pair of endless traveling chains 1, connected with each other 20 by a series of slats 2 which extend transversely of the frame and have their ends secured to the links of the chains 1. These slats serve as the support for the filled bags or other packages being conveyed. In order 25 to cause this apron to move longitudinally of the frame, a driving mechanism of a particular character is employed. This driving mechanism essentially includes a shaft 5 which extends longitudinally of the frame 30 and has a driving connection with the apron whereby upon its rotation it will impart traveling movement to the latter in the direction of the length of the shaft, and also has at its end an element 8 of a universal 35 connection, the mate 8^a of which is carried by the contiguous end of the similar shaft 5^a of the next section A'. This driving connection, for the type of apron conveyer herein illustrated, essentially includes sprockets 40 3 which are engaged by the chains 1 and are mounted on shafts 4 at the opposite ends of the frame, and toothed gearing connecting the shaft 4 at the driving end of the frame with the shaft 5. A most desirable form of 45 gearing consists of a bevel gear 6 fixed on the shaft 5 and a similar gear 7 fixed on the contiguous shaft 4 and intermeshed with the gear 6.

The frame of the section A is composed of 50 longitudinal side bars 10 formed of angle irons constituting tracks for the chains 1, which chains are preferably provided with rollers 1^x which run on said tracks and minimize friction. These longitudinal members 55 at each side of the frame are connected with each other by vertical straps or members 11 and also by diagonal members 12 and the two side frames thus formed are connected with each other by transverse members 13 60 which are arranged at intervals and are riveted or otherwise strongly secured to the vertical members 11 at places between the working and returning runs of the apron, as shown in Fig. 9, whereby the frame is 65 strongly braced. The frame is also mounted

upon wheeled supports, located under the ends thereof and secured thereto. These supports are here shown as comprising vertical members 14 and transverse members 15, each composed of angle irons, strongly secured together and provided with supporting wheels 16. This wheeled support is of such construction as to adapt it to also support a suitable prime mover C and for this purpose comprises uprights 17 and suitable 70 means supported thereby for the motor and the driving connections. The motor here shown is electric and is shown as driving a shaft 20 by intermediate reducing gears comprising gears 21, 22, shaft 23 and gears 24 and 24^a. Upon the shaft 20 there is mounted a sprocket wheel 24^b which drives a chain 24^c serving to communicate movement to a second sprocket wheel 24^d fixed on the shaft 5. 85

The section A' may be, and is here shown as, identical in construction with that of the section A, except for such changes as are necessary to adapt it to be driven by the shaft 5 of the latter, instead of by a prime 90 mover. Hence, there is no provision in it for the prime mover C, and its longitudinal shaft (5^a) instead of having a universal-joint member 8^a at one end only, has such a member at both ends, whereby it is adapted for connection with the shaft 5 at one end and also with a similar shaft at its other end, forming part of the next section. It will be apparent that rotative movement imparted to the shaft 5^a from the shaft 5 will operate, 95 through the gears 6^a and 7^a and sprocket wheels 3^a and the shafts of the latter, to transmit traveling movement to the apron of the section A' in the direction of the length of the frame of the latter, precisely 100 the same as the shaft 5 causes traveling movement to be imparted to the apron of the section A. 105

It will be observed that the described universal connection enables the sections A and A' to be arranged at any desired angle 110 with reference to each other without interfering with the transmission of movement to the apron of one section from the shaft of the preceding section. 115

In order also that the sections may be readily disconnected and reunited, the complementary members or mates 8 and 8^a of the universal connection are connected with each other by readily removable connection, 120 as pins 9 removably extending through the spiders 9^a in the type of universal connection herein shown.

In practice, the system will include a section A and several sections A', placed together end to end, in direct line with each other or at an angle or angles, to accord with required conditions, and where the conditions are variable, sections may be removed from or added to the line, and moved read- 125 130

ily from place to place, all as herein set forth.

The motor C, in practice, has a controller whereby it may drive the apron in either direction; and each section A and A' has at one end provision for taking up slack in the chains, which need not be set forth in detail herein, as it forms no important part of my invention. It preferably is substantially 10 identical with that of the elevator herein-after described.

The elevator B comprises two frames which are rigidly secured together. One of these frames supports and guides the apron 15 and is herein termed the apron-frame. The other supports the apron-frame and is arranged thereunder and is termed the base-frame. This base-frame extends under the whole or approximately the whole length of 20 the apron-frame and engages the opposite ends of the latter. It is carried upon wheels arranged under its ends, the wheels under one end being connected to what is referred to herein as a carrier, to which the draft 25 is applied through the handle 100 when the elevator is being moved from place to place. This carrier is mounted to turn relatively to the base-frame and suitable elements are employed to facilitate this turning movement. The several parts referred to are of 30 special and very advantageous construction in the herein-exemplified form of the invention, and will now be set forth in detail. The apron-frame has approximately horizontal upper and lower ends b and b' and an inclined section b² intermediate of these ends and gradually merging into the same. The lower end b is in the plane of the contiguous section A', and the upper end may 35 be in the plane of another conveyer indicated by the dotted line A², which may be an apron conveyer like that already described, or a power or gravity conveyer of any suitable construction. The transfer of 40 the packages from said conveyers to the elevator, or from the elevator to said conveyers, is thus accomplished without shock either to the package or to the mechanism. The gradual mergence of the inclined section 45 of the conveyer into the horizontal portions thereof, eliminating as it does abrupt angles at the junction of these parts, causes the packages to move readily and easily and without shock, across or along the junction points, and thereby materially improves the 50 operation of the parts.

The apron frame is composed of a pair of suitably connected longitudinal members 25 and 26 at each side thereof. These members 55 are formed of angle irons, whereby they are light and strong and at the same time form ways or tracks for the endless chains 27 which, together with transversely-arranged sets 28, constitute the apron of this conveyer. The chains travel over sprockets 29

at the base and head of the elevator and suitable elements, as 30, are arranged at the junction of horizontal and inclined portions of the frame, to hold the chains down into the plane of the upper frame elements 70 25 at these places. Similar guiding means as 30^a may be provided for the returning or lower runs of the chains. At intervals along the length of this apron means, as strips 31 projecting above the plane of the 75 surface thereof, are provided to prevent movement of the packages upon the apron.

The base-frame has two lower side members, 32, preferably formed of angle iron in order that they may be both light and 80 strong. These members extend from the lower end of the elevator, in horizontal alignment, or approximately so, with the lower members 26 of the apron-frame, to a place which is approximately in vertical 85 alignment with the upper end of the elevator. They preferably overlap the apron-frame members 26 at their forward ends.

Frame members are employed to connect the apron-frame with said members 32. 90 Those here shown, comprise vertical members 33, having their upper ends secured to the apron frame members 25 and 26 at the upper end of the elevator; other vertical members 34 extending from the members 32 and fastened to the side members 25 and 26 intermediate of the length of the apron-frame; horizontal members 35 secured to the vertical members 33 about midway the length of the latter and extending 100 to the apron-frame members 25 and 26 to which they are rigidly secured; diagonal truss rods or members 36, secured at their ends to the longitudinal members 32, at places adjacent to the lower ends of the vertical members 34, and also secured to the apron-frame members; other diagonal members 37, the lower ends of which are arranged and secured contiguous to the junctions of members 33 and 35, and the upper ends of which are secured to said apron-frame members between said members 35 and the upper ends of the elevator; and still other diagonal members 38, the lower ends of which are secured at or 110 adjacent to the junction of the members 32 and 33 and the upper ends of which are secured to the apron-frame members 25 and 26, at places between the members 34 and 35. All of these members are preferably 115 made of angle iron.

Straps, as 39, are preferably arranged at intervals along the length of the apron-frame and connect with each other the members 25 and 26, at each side of said frame. 125 These straps are preferably connected with each other transversely of the apron frame, by tie-rods 39^a. The vertical members 33 are connected with each other by bracing members, herein shown as composed of hori- 130

zontal and diagonal elements 40 and 41, respectively.

One end of the supporting frame includes what may be generically referred to as a platform, to which the wheeled carrier hereinbefore referred to is connected. In the exemplified form herein shown this is arranged under the elevated end of the elevator and at the junction of the members 32, 33 and 38. It is formed to provide an annular channel 42 a side wall of which furnishes bearings for a series of shafts 43 upon which are mounted wheels 44 by which this end of the frame is supported by the wheeled carrier. This wheeled carrier comprises a frame 45, having pendent bearings 46 for the shaft 47 of the carrying wheels 48 and a ring 49 which is arranged in juxtaposition to the inner wall (51) of the channel 42 and serves as a guide in the pivotal movement of the carrier. The wheels 44 make this movement an easily-accomplished one. In the exemplified form, they are carried by the base frame and run upon the carrier, the latter preferably being provided with a wear plate 50, here shown as integral with the ring 49.

The channel 42 is here shown as formed by an annular angle ring 52 and a separate ring 51 relatively disposed to close three sides of the channel, the fourth side being formed by the wear plate 50.

In the exemplified form of the invention, both the platform and carrier are thus of open annular form.

From the foregoing description it will be seen that the rear end of the elevator is movably mounted to swing upon an arc while leaving its lower or receiving end disposed in operative relation to the conveyer sections by virtue of which it is possible to move the discharge end of the elevator as the operation of piling the packages goes on so that these packages may be piled to the best advantage.

The several frame-members and the platform are secured together preferably as follows:

The lower ends of the members 33 are cut away for the reception of the contiguous ends of the members 32, and the lower ends of the members 38 abut against the side walls of the members 33. At the junction of these parts plates 55 are arranged and serve to secure together the several members referred to, being riveted thereto as shown. These plates may also be riveted, or otherwise suitably secured to the platform, and this is true also of the members 32, where by a rigid connection is made between the platform and the frame. The platform also supports a frame composed of legs 56 which diverge thereto from a place immediately under the tie-members 40 of the uprights 33, to which tie members they are suitably

secured. The lower ends of these legs are secured to the platform by brackets or plates 57 riveted or otherwise suitably secured to the parts referred to, and cross pieces 58 are provided which brace the platform.

As already stated, the other end also of the elevator is mounted upon wheels (59) connected thereto in any suitable manner as by means of a frame having a member 60 which extends across the lower end of the frame, underneath the same, and vertical members 61 which rise from the members 60 and are secured to the apron-frame members 25 and 26 at each side of the elevator. Suitable provision is made at this end of the elevator for taking up slack in the chains. The means shown for this purpose comprise bearings 62 for the shaft 63 of the sprockets, said bearings being slidably mounted in supports 64, with suitable provision between the same for guiding the bearings in their adjustments. The bearings are adjusted by hand wheels 65, or other suitable means, mounted on rods 65* threaded in the supports.

The uprights 33 support a slide 66, through intermediate means which enable the outer end of the slide to be raised or lowered and to be moved laterally, in order to direct the packages to different predetermined parts of the pile, within the range of its said adjustments. The intermediate means referred to are herein shown as composed of brackets 67 secured to the frame members 33 and providing bearings for a shaft 68 upon which is mounted a frame 69 having lugs or ears 70 which engage the shaft 68, and a pivotal connection, as the vertical pivot bolt 71, between the frame 69 and the rear end of the slide 66. A plate 72, which has depending ears or lugs 73 at its ends, is also mounted upon the shaft 68, under the center of the frame 69, thus bracing the rear end of the slide at this place, where the greatest strain is imposed. Some suitable means, as clamping nuts 74 upon the ends of the shaft 68 will be provided to hold the frame 69 and slide in the position to which they are adjusted upon the shaft 68, as the axis of such adjustment. The nut 75 upon the pivot bolt 71 similarly secures the slide in its horizontal adjustment upon the frame 69.

For driving the apron, an electric motor as 76 mounted upon a base 77 carried by the members 32 is preferably employed. This motor is suitably connected with the apron, as by means of a belt 78 extending over a pulley 79 mounted on a countershaft 80 carrying a pinion 81 which meshes into a gear 82 mounted on the shaft 83 of the upper sprockets of the apron. This constitutes a form of reducing gearing preferably employed. The members 88 carry a shield 84 mounted over the motor 76 and protecting

the latter against drippings from the packages. The motor is preferably connected with a controller, not necessary to show herein; adapted to cause it to run the chain either forward or backward; thus adapting the elevator to lower as well as to raise packages.

It is believed that from the foregoing the construction, operation and advantages of my present invention will be clearly understood and that while the details are in many respects advantageous yet changes may be made in the details without departing from the spirit of the invention, or the scope of the subjoined claims.

Having thus described my invention, what I believe to be new, and desire to secure by Letters Patent and what I, therefore, claim is:

20 1. In a conveyer, an elevator comprising a plurality of frames one of which supports the other, and has members by which it is connected to the opposite ends of the latter, said latter frame being inclined and provided with an endless-traveling package-conveying means, a platform at the junction of said members, a wheeled carrier mounted to turn with reference to said platform, rotative elements between the platform and carrier, said platform and carrier relatively constructed to provide a channel for the rotative elements, and a wheeled support for the other end of the elevator.

35 2. In a conveyer, an elevator comprising a plurality of frames one of which supports the other, and has members by which it is connected to the opposite ends of the latter, said latter frame being inclined and provided with an endless-traveling package-conveying means, a platform at the junction of said members, a wheeled carrier mounted to turn with reference to said platform, said platform having concentric annular portions and the carrier having a projection concentric with and contiguous to one of said portions, rotative elements engaging the carrier and platform and mounted in the channel between two of said concentric portions, and a wheeled support for the other end of the elevator.

50 3. In a conveyer, the combination with an inclined frame and an endless package-supporting means which travels longitudinally thereof, of a slide-supporting frame arranged near the discharging portion of said endless traveling means, a supporting means for the slide-supporting frame, the slide supporting frame being pivotally mounted for adjustment on a horizontal axis relatively to its said supporting means, and a slide carried by the slide-supporting frame and mounted for adjustment relatively thereto on a vertical axis.

4. In a conveyer, the combination with an inclined apron frame, an endless traveling apron movable longitudinally thereof, and a supporting means for the apron frame, said supporting means having a transverse shaft below the discharging portion of the apron, of a slide-supporting frame having ears mounted on said shaft and pivotally adjustable upon the same, and a slide pivotally attached to said slide-supporting frame so as to be adjustable on a vertical axis thereupon.

75 5. In a conveyer, an inclined frame having an endless traveling package conveying means extending to the upper end thereof, uprights arranged under the upper end of the frame and supporting the same, a transverse member carried by the uprights, and a slide pivotally mounted on the transverse member.

6. In a conveyer, an inclined frame having an endless traveling package conveying means extending to the upper end thereof, uprights arranged under the upper end of the frame and supporting the same, a transverse frame pivotally connected with the uprights, and a slide the rear end of which is supported by the frame, said slide pivotally connected to the transverse frame.

7. In a conveyer, an inclined frame having an endless traveling package-conveying means, supports for the inclined frame, arranged under the upper end thereof, a transverse shaft supported by said supports, a slide-supporting frame, mounted on said shaft and pivotally adjustable thereon, the slide-supporting frame having ears which engage the shaft, and a slide pivotally mounted to turn on a vertical axis on said slide-supporting frame.

8. The combination with an endless conveyer including a frame, of an endless traveling bed supported thereon, said conveyer having an approximately horizontal lower end portion, an approximately horizontal upper end portion, and an inclined portion arranged between and gradually merging into the upper and lower end portions, a substantially right angular supporting frame located beneath the conveyer and connected with the upper and lower horizontal portions of such conveyer, a turn table upon which the meeting sections of the right angular frames rest and traction devices for the turn table.

In testimony whereof I affix my signature, in presence of two witnesses.

MORRIS U. BERNHEIM.
